(57) **CLAIM**

The ornamental design for a golf tool for repairing divots and tightening cleats, as shown and described.

DESCRIPTION

FIG. 1 is a lower, frontal perspective view showing the new design;

FIG. 2 is a top view thereof;

FIG. 3 is a left side view thereof;

FIG. 4 is a front view thereof; and,

FIG. 5 is a right side view thereof.

The rear of the article is unadorned and appears in outline as a mirror image of FIG. 4.

The broken lines showing environment in the drawing are for illustrative purposes only and form no part of the claimed design.
